US0D1059103S

(12) **United States Design Patent** (10) **Patent No.:** **US D1,059,103 S**
(45) **Date of Patent:** **** Jan. 28, 2025**

(54) **CHAIR**

(71) Applicant: **SMITH SYSTEM
MANUFACTURING COMPANY,**
Carrollton, TX (US)

(72) Inventors: **Keith Robert Machin**, Hopkins, MI
(US); **David J. Battey**, Caledonia, MI
(US); **David O. Morton**, Grand Rapids,
MI (US)

(**) Term: **15 Years**

(21) Appl. No.: **29/853,399**

(22) Filed: **Sep. 15, 2022**

(51) LOC (15) Cl. **06-06**

(52) U.S. Cl.

USPC **D6/375**; D6/716

(58) **Field of Classification Search**

USPC D6/334-336, 338, 341, 365, 366,
D6/374-376, 379, 380, 716, 716.1, 716.4
CPC A47C 3/04; A47C 3/12; A47C 5/12; A47C
7/029; A47C 7/40; A47C 7/16; A47C
4/02; A47C 4/03

CLAIM

The ornamental design for a chair as shown and described.

DESCRIPTION

FIG. 1 is a top-front perspective view of a chair according to the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom-back perspective view thereof.

The broken lines show portions of the chair that form no part of the claimed design.

1 Claim, 8 Drawing Sheets
